(57) **CLAIM**

The ornamental design for a citrus juice squeezing device, as shown and described.

DESCRIPTION

FIG. 1 is a top, front perspective view of a citrus juice squeezing device according to the present invention;

FIG. 2 is a top plan view thereof;

FIG. 3 is a bottom plan view thereof;

FIG. 4 is a right side elevation view thereof;

FIG. 5 is a left side elevation view thereof;

FIG. 6 is a left side elevation view thereof shown in a closed position;

FIG. 7 is a front elevation view of the device of FIGS. 1–5 in the open position; and,

FIG. 8 is a rear elevation view thereof.
